US00D908371S

(12) United States Design Patent (10) Patent No.: US D908,371 S
(45) Date of Patent: * Jan. 26, 2021

(54) PHOTO FRAME

(71) Applicant: Bingyan Wang, Guangdong (CN)

(72) Inventor: Bingyan Wang, Guangdong (CN)

(73) Assignee: Shenzhen New Fruit Technology Co., Ltd., Shenzhen (CN)

() Term: 15 Years

(21) Appl. No.: 29/737,060

(22) Filed: Jun. 5, 2020

(51) LOC (13) Cl. 06-07

(52) U.S. Cl.

USPC D6/300

(58) Field of Classification Search

USPC D6/300-314; D25/136

See application file for complete search history.
